UNITED STATES PATENT OFFICE.

JOHN H. CIRINA, OF BROOKLYN, NEW YORK, ASSIGNOR OF ONE-HALF TO FRANK LANZETTA, OF BROOKLYN, NEW YORK.

CHOKE-ROD-ADJUSTING DEVICE.

Application filed February 12, 1923. Serial No. 618,730.

To all whom it may concern:

Be it known that I, JOHN H. CIRINA, a citizen of the United States, residing at Brooklyn, in the county of Kings and State 5 of New York, have invented certain new and useful Improvements in Choke-Rod-Adjusting Devices, of which the following is a specification.

This invention relates to devices for adjusting the position of the choke rod of an 10 automobile of the Ford type when starting the engine.

It is well known that in attempting to start the engine, particularly in cold 15 weather, that the choke rod must be raised to its extreme position, thereby cutting off the supply of air, but that the rod generally drops by gravity and thus requires the same to be raised continually until the 20 engine operates smoothly and regularly. In some instances it is not necessary to raise the choke rod to its maximum position to start the engine, and in so far as I am aware, no devices have been in use wherein the 25 raising and lowering of the said choke rod could be effected whereby the proper gas and air mixture could be had as necessity requires.

The object, therefore, of my invention is 30 the provision of a clamping device and guide adapted for cooperation with the choke rod so that the same can be raised and lowered when starting the engine. In order to more fully understand my invention, attention is directed to the following drawings, showing a preferred embodiment thereof, wherein;

Figure 1 is a view showing the application 40 of my invention to the choke rod, leading to the carburetor, not shown.

Figure 2 is a plan of the attachment or clamp and

Figure 3 is a side view.

Referring now to the drawings wherein 45 like reference characters designate corresponding parts throughout the several views, 5 designates a section of the instrument board and 6 the choke rod, extending therethrough, the upper end of said 50 rod having a hand knob 7 whereby said rod may be raised and lowered as required. A plate 8 provided with a flange 9 is secured beneath the instrument board 5 through the medium of the screws or fastening element 55 10. The plate 8 is provided with an arm or

extension 11, said arm being bent slightly outwardly as at 12 and disposed at an obtuse angle toward its end 13, said arm constituting the stationary part of the device. Reference being had to Figures 2 and 3 of the 60 drawing, it will be seen that the plate 8 is provided with apertures 14, which receive the inwardly bent tongues 15, formed on the end of a movable arm or plate 16, it being observed that the said plate is also bent opposite to the portion 12 and that the end of the said plate 16 is also disposed at an obtuse angle toward its end 17 so as to form a Y on the extreme outer end. A coil spring 18 is connected at one end 19 to the stationary plate and at its opposite end 20 to the movable plate. The tongues 15 above referred to are not clamped to the plate 8, but on the other hand extend freely through the apertures 14 so that the plate 16 may 75 pivot for movement against the resistance of the spring 18.

In assembling the device, after the plate 8 has been screwed to the instrument board, the movable arm 16 is brought toward the 80 choke rod 6 and in contact with the same whereupon the end of the coil spring 18 is secured thereto, thus clamping and gripping the rod but permitting the same to be raised and lowered since said rod is held purely 85 by the said arm 16. In this manner, it will be seen that various degrees of adjustment may be had as when starting an engine, particularly in cold weather, and after the desired effect is had, the rod 6 may be 90 lowered to its normal position as is well understood.

While I have illustrated and described my invention with some degree of particularity, I realize that in practice various 95 alterations therein may be made. I therefore reserve the right and privilege of changing the form of the details of construction or otherwise altering the arrangement of the correlated parts without departing 100 from the spirit of the invention or the scope of the appended claims.

Having thus described my invention what I claim as new and desire to secure by 105 United States Letters Patent is:—

1. In combination with the choke rod of an air regulating valve, a stationary arm, an arm pivoted to the stationary arm and frictionally engaging the choke rod and resilient means connecting the free ends of 110

said arms permitting the sliding movement of said rod.

2. In combination with the choke rod of an air regulating valve, a stationary arm, 5 an arm pivoted to the stationary arm and frictionally engaging the choke rod and a spring connecting the outer ends of the stationary and movable arms permitting the sliding movement of the choke rod to various positions.

3. In combination with the choke rod of an air regulating valve, a stationary arm

having apertures therein and a flange for connection to the dash board of the automobile, a movable arm provided with tongues 15 at one end extending through the said apertures, the opposite ends of said arms being bent in opposed directions and resilient means connecting the bent ends of the arms permitting the choke rod to slide to various, 20 adjusted positions.

In testimony whereof I affix my signature.

JOHN H. CIRINA. [L. S.]
